CLAIM

The ornamental design for a LED light, as shown and described.

DESCRIPTION

FIG. 1 is a front elevational view of a LED light showing my new design;

FIG. 2 is a rear elevational view thereof;

FIG. 3 is a left side view thereof;

FIG. 4 is a right side view thereof;

FIG. 5 is a top plan view thereof;

FIG. 6 is a perspective view thereof;

FIG. 7 is a second perspective view thereof;

FIG. 8 is a third perspective view thereof;

FIG. 9 is a perspective view thereof with a cover attached to the LED light; and,

FIG. 10 is a perspective view thereof with another cover attached to the LED light.

The broken lines shown in FIG. 2 illustrate portions of the LED light, the broken lines showing the cover illustrate environmental structures; all broken lines form no part of the claim.

1 Claim, 10 Drawing Sheets(56)
